[57] CLAIM

The ornamental design for an oval palm brush handle, as shown and described.

FIG. 1 is a top perspective view of an oval palm brush handle showing our new design;

FIG. 2 is a top plan view thereof;

FIG. 3 is a bottom plan view thereof;

FIG. 4 is a right side elevational view thereof, the left side elevation view being identical to the right side view shown;

FIG. 5 is a front elevational view thereof, the rear elevation view being identical to the front view shown;

FIG. 6 is a top plan view of a hair brush showing a first alternative embodiment of our new design with the only difference residing in the oval surface design on the top and bottom surfaces;

FIG. 7 is a bottom plan view of the first alternative embodiment;

FIG. 8 is a top plan view of a hair brush showing a second alternative embodiment of our new design;

FIG. 9 is a bottom plan view of the second alternative embodiment;

FIG. 10 is a right side elevational view of the second alternative embodiment, the left side elevation view being identical to the right side view shown; and,

FIG. 11 is a front elevational view of the second alternative embodiment, the rear elevation view being identical to the front view shown.

The broken line illustration showing the position of bristles in FIG. 1 is for illustrative purposes only and forms no part of the design covered by the following claim.
